US00D965153S

(12) **United States Design Patent** (10) **Patent No.:** **US D965,153 S**
(45) **Date of Patent:** **** Sep. 27, 2022**

(54) **BACK BRACE**

(71) Applicant: **Shenzhen Daochi Electronics Co., Ltd.**, Shenzhen (CN)

(72) Inventor: **Yongli Liang**, Shenzhen (CN)

(73) Assignee: **Shenzhen Daochi Electronics Co., Ltd.**, Shenzhen (CN)

(**) Term: **15 Years**

(21) Appl. No.: **29/748,418**

(22) Filed: **Aug. 28, 2020**

(51) LOC (13) Cl. **24-02**

(52) U.S. Cl.

USPC **D24/190**
